UNITED STATES PATENT OFFICE.

ARTHUR SENGER, OF MILWAUKEE, WISCONSIN.

DESIGN FOR AN AUTOMOBILE-LENS.

56,259.

Specification for Design.

Patented Sept. 7, 1920.

Application filed April 26, 1920. Serial No. 376,884. Term of patent 3½ years.

To all whom it may concern:

Be it known that I, ARTHUR SENGER, a citizen of the United States, residing at Milwaukee, in the county of Milwaukee and State of Wisconsin, have invented a new, original, and ornamental Design for an Automobile-Lens, of which the following is a specification, reference being had to the accompanying drawing, forming part thereof.

Figure 1 is a front elevation, and

Fig. 2 is a vertical section.

I claim:

The ornamental design for an automobile lens, as shown.

In testimony that I claim the foregoing I have hereunto set my hand at Milwaukee, in the county of Milwaukee and State of Wisconsin.

ARTHUR SENGER.
